3 Claims

ABSTRACT OF THE DISCLOSURE

A potentiometer including a leadscrew having an O-ring mounted in an annular groove formed in the head portion of the leadscrew. The groove positions the O-ring on the leadscrew and permits the leadscrew to be "dropped" into the potentiometer during the assembly of the potentiometer. Cooperating case halves compress the O-ring around the lead screw to seal the end of the potentiometer through which the leadscrew extends.

Conventional potentiometers include an elongated leadscrew which is mounted in the potentiometer by feeding the same through an O-ring bearing hole at one end thereof. The leadscrew is then held in place by a spring clip, roll pin, etc.

Therefore, it is a principal object of this invention to provide a potentiometer which is constructed to permit "drop-in" construction.

A further object of this invention is to provide a potentiometer including a leadscrew having an O-ring positioned in an annular groove formed in the head portion of the leadscrew.

A further object of this invention is to provide a potentiometer having a unique means for sealing the end of the potentiometer through which the head portion of the leadscrew extends.

A further object of this invention is to provide a potentiometer which reduces the assembly time and the material costs.

A further object of this invention is to provide a potentiometer wherein an O-ring is compressed between cooperating case halves to seal one end of the potentiometer.

A further object of this invention is to provide a potentiometer which prevents moisture failures of the potentiometer.

A further object of this invention is to provide a potentiometer wherein the 360 degree bearing hole is eliminated.

A further object of this invention is to provide a potentiometer which includes a leadscrew having means thereon to position the same thereby eliminating the need for additional parts such as spring clips, roll pins, etc.

A further object of this invention is to provide a potentiometer which is economical of manufacture, durable in use and refined in appearance.

These and other objects will be apparent to those skilled in the art.

This invention consists in the construction, arrangements, and combination of the various parts of the device, whereby the objects contemplated are attained as hereinafter more fully set forth, specifically pointed out in the claims, and illustrated in the accompanying drawings in which:

FIG. 1 is an exploded perspective view of a portion of the potentiometer;

FIG. 2 is an enlarged sectional view of the potentiometer as seen along line 2—2 of FIG. 1;

FIG. 3 is a sectional view as seen along lines 3—3 of FIG. 2;

2

FIG. 4 is a fragmentary exploded perspective view of the potentiometer illustrating the cooperating case halves and their relationship to the O-ring on the leadscrew; and

FIG. 5 is a fragmentary end view of the potentiometer.

The potentiometer of this invention is generally designated by the reference numeral 10 and generally includes a case 12 and a lid 14. Case 12 is constructed of suitable dielectric material such as plastic or the like. Case 12 includes opposite ends 16 and 18, opposite sides 20 and 22, bottom 24 and top 26. Case 12 also includes a compartment 28 extending downwardly from the upper end thereof and which has a resistance coil 30 operatively mounted therein, the opposite ends of which are connected to terminals 32 and 34 extending downwardly through slots 36 and 38 respectively through the bottom of the case, as illustrated in the drawings. The numeral 40 generally designates an adjustment screw having an elongated threaded portion 42 and a head portion 44 mounted at one end thereof. A wiper arm assembly 46 is operatively connected to the threaded portion 42 of screw 40 for longitudinal movement therealong and operatively engages the resistance coil 30. Wiper arm assembly 46 is operatively connected to a collector bar means (not shown) which would be operatively connected to a terminal (not shown) extending downwardly through the bottom of the case.

Case 12 is provided with a recessed area generally indicated by the reference numeral 48 which is adapted to receive the lid 14 therein. Case 12 is provided with an upstanding tab 50 having an opening 52 extending downwardly thereto as best illustrated in FIG. 1. Opening 52 is generally semi-circular in shape but embraces more than 180 degrees or one-half of the threaded portion 42 of the screw 40 so that the threaded portion 42 may be snapped into the opening 52 thereby yieldably detachably maintaining the same therein. Case 12 is also provided with a shoulder 54 which is adjacent the tab 50 and having an arcuate opening 56 formed therein.

Head portion 44 of screw 40 includes a generally cylindrical shaped portion 58, an annular shoulder 60, and a peripheral groove 62. As seen in FIG. 2, the outer end of the head portion 44 is slotted at 64 to accommodate a screwdriver to permit the rotation of the screw. The numeral 66 generally designates an O-ring which is mounted in the groove 62 as best illustrated in FIG. 2. Case 12 is provided with a semi-circular opening 68 which receives the lower half of the O-ring 66 therein. Case 12 is also provided with a groove 70 formed therein which receives the lower end of the shoulder 60 as best illustrated in FIG. 2. Cylindrical shaped portion 58 of head 44 is received by a generally semi-circular shaped groove 72 which is spaced inwardly of an opening 74. Opening 74 is generally semi-circular in shape but embraces slightly more than 180 degrees or half of the cylindrical shaped portion 58 of head portion 44 so that the head portion 58 may be "snapped" into the opening 74 to yieldably maintain the leadscrew in the case 12.

Lid 14 includes a top 76, bottom 78, opposite ends 80 and 82 and opposite sides 84 and 86. Lid 14 has a tab 88 extending downwardly therefrom inwardly of end 80 which is provided with an arcuate opening 90 formed therein. When the lid 14 is in place as illustrated in FIG. 2, opening 90 partially receives the upper end of the threaded portion of the leadscrew while tab 88 is positioned above shoulder 54. The numeral 92 designates a finger element extending outwardly from the opening 90 which is positioned over the upper surface of the threaded portion 42 of the leadscrew 40. Lid 14 is also provided with a tab 94 extending downwardly therefrom inwardly of its end 82 which has an arcuate opening 96

formed therein as illustrated in FIG. 1. When the lid 14 is in place, opening 96 receives the upper end of cylindrical shaped portion 58. A tab 98 is positioned at end 82 of lid 14 and extends downwardly therefrom as best illustrated in FIG. 4. Tab 98 is provided with a semi-circular opening 100 formed therein which is adapted to receive the upper half of the O-ring 66. As illustrated in FIG. 4, the tab 98 is received in the opening 102 formed in case 12. Tab 98 is also provided with various weld beads 104 while the underside of lid 14 is provided with a weld bead 106 extending therearound. The potentiometer is easily assembled by "drop-in" fabrication due to the open nature of the upper end of case 12. The resistance coil, terminal, wiper arm assembly and collector bar means are easily inserted into the compartment 28 through the open upper end thereof. The screw 40 is "dropped" into the case 12 and snapped into place in its openings 52 and 74. The O-ring 66 is mounted in the groove 62 prior to the screw being inserted into the case 12 and the O-ring 66 and the shoulder 60 serve to position the screw in the case 12. The lid 14 is then installed on case 12 and the opening 100 and tab 98 and the opening 68 cooperate to compress the O-ring 66 around the head portion of the screw. The O-ring 66 is forced out from between the cooperating surfaces of the case 12 and lid 14 by the shape of the weld bead. The potentiometer may then be sealed by the use of ultrasonic welding which causes the various weld beads to melt and further push the O-ring into the head portion of the screw. The process and the design just described prevents pinching of the O-ring between the cooperating surfaces of the case 12 and lid 14 which could cause damage to the O-ring and which could cause moisture failure of the potentiometer.

Thus it can be seen that the drop-in screw reduces labor costs because it does not need to be fed through an O-ring bearing hole as must be done in conventional potentiometers. Additionally, the design described herein eliminates the need for a spring clip, roll pin, etc. to maintain the screw in place in the case. The absence of such a spring clip or the like also reduces the total cost of the unit. The lack of the O-ring bearing hole in the case reduces the cost of the part because of faster cycling time since the mold does not need to contain core pins for such an opening.

Thus it can be seen that a unique means has been provided for sealing one end of a potentiometer through the use of cooperating case halves which compress the O-ring around the head portion of the lead screw. Thus it can be seen that the potentiometer accomplishes at least all of its stated objectives.

Some changes may be made in the construction and arrangement of my potentiometer without departing from the real spirit and purpose of my invention, and it is my intention to cover by my claims, any modified forms of structure or use of mechanical equivalents which may be reasonably included within their scope.

I claim:

1. In a potentiometer, a case having upper and lower ends, opposite ends and 60 opposite sides, said upper end being open, said case having a compartment formed therein extending downwardly thereinto from its open upper end,

an elongated resistance means in said compartment operatively connected to a first and second terminal means,
 an adjustment screw rotatably mounted in said case and having a head portion mounted at one end thereof, said screw having a threaded portion, said head portion being rotatably mounted in one of said ends of said case,
 a wiper arm assembly operatively mounted on said screw in said compartment for longitudinal movement therealong, said wiper arm operatively engaging said resistance element and being operatively connected to a third terminal means,
 said screw head portion having a peripheral slot extending therearound,
 an O-ring mounted in said slot,
 and a lid mounted on said case sealably closing the upper end of said compartment and engaging said O-ring to compress the same between said lid and said case to seal the one end of the potentiometer through which said screw head portion extends, said case having adjustment screw supporting areas at each of its ends adapted to support said adjustment screw in said case,
 each of said supporting areas having an opening formed therein extending downwardly thereinto adapted to rotatably receive opposite ends of said adjustment screw, said openings having open upper ends to permit said adjustment screw to be placed in said case downwardly through the open upper end of said case and downwardly into said openings in said supporting areas,
 said openings being semi-circular in shape and rotatably embracing said adjustment screw greater than 180 degrees but less than 360 degrees to yieldably detachably maintain said screw in said case.

2. The potentiometer of claim 1 wherein said case has a semi-circular opening at its said one end which receives a portion of said O-ring, said lid having a tab extending downwardly from one end thereof, said tab having a semi-circular opening formed therein which receives a portion of said O-ring.

3. The potentiometer of claim 1 wherein one of said openings receives one end of the threaded portion of said adjustment screw and the other of said openings receives said screw head portion.
